[57] CLAIM

The ornamental design for a pacifier handle, as shown and described.

DESCRIPTION

FIG. 1 is a front elevational view of a pacifier handle showing my new design;

FIG. 2 is a right side elevational view thereof, the left side being a mirror image thereof;

FIG. 3 is a top plan view thereof;

FIG. 4 is a bottom plan view thereof; and

FIG. 5 is a rear elevational view thereof. The broken line showing of the nipple in FIGS. 2, 3 and 4 is for illustrative purposes only and forms no part of the claimed design.

FIG. 3

FIG. 1

FIG. 2

FIG. 4

FIG. 5
